SELECTIVE SMOKE DETECTOR

Harry Campbell Grant, Jr., New York, N. Y., assignor to Walter Kidde & Company, Inc., New York, N. Y., a corporation of New York

Application November 11, 1931, Serial No. 574,339

10 Claims. (Cl. 177—311)

The present invention relates to mechanisms for detecting the presence and location of smoke and embodies, more specifically, an improved smoke detecting mechanism wherein a single automatic smoke detector is provided to indicate the presence and location of smoke selectively in a plurality of separate compartments.

More particularly, the invention embodies a detecting mechanism of the above character wherein a substantially continuous flow of fluid from all compartments protected is maintained in order that the indication of smoke by the detecting mechanism may accurately indicate the condition of the particular compartment or zone to which the indicating mechanism is connected at the time of the indication.

Previous development in this field has resulted in the provision of detecting mechanisms wherein a suction is created successively in a plurality of pipe lines leading from spaces to be protected. The suction is periodically connected to the various lines in rotation and fluid thus extracted from the respective sections and introduced into a suitable testing or detecting mechanism. Where systems of this character become complex, the appreciable interval of time between the initial presence of smoke in a compartment and its arrival at the detecting mechanism has been found to be highly objectionable even to the extent of rendering the apparatus ineffective.

In order that a mechanism may be provided wherein the fluid extracted from the respective compartments travels continuously from all of such compartments, the present invention has been designed and an object thereof is to provide a single smoke detecting mechanism for one or more protected areas, means being provided to afford an indication of the existence of smoke in such area or areas, the mere momentary presence of smoke initiating an indication which persists.

A further object of the invention is to provide a detecting mechanism wherein the plurality of fluid streams from the protected areas flow continuously, a mechanism being provided to take samples of the fluid stream successively and activate an indicating mechanism in the event that smoke particles exist therein.

A further object of the invention is to provide in combination with the last named mechanism, a means for providing a persisting indication upon the momentary presence of smoke in the stream of one of the fluid conductors from the protected areas.

55 Further objects, not specifically enumerated

above, will be apparent as the invention is described in greater detail in connection with the accompanying drawings, wherein:

Figure 1 is a view in elevation, partly broken away and in section, showing a detecting mechanism constructed in accordance with the present invention.

Figure 2 is a view in section, taken on line 2—2 of Figure 1, and looking in the direction of the arrows, a portion of the housing being broken away in the interest of clearness to show the manner in which fluid is directed to the indicating mechanism successively from the respective protected areas.

Figure 3 is a view in section, taken on line 3—3 of Figure 1, and looking in the direction of the arrows.

Figure 4 is a view in section, taken on line 4—4 of Figure 1, and looking in the direction of the arrows.

Figure 5 is a diagrammatic representation of an electrical system for actuating a suitable signalling mechanism upon the existence of smoke in the detecting chamber.

Figure 6 is a view similar to Figure 1, showing a modified form of detecting mechanism.

Figure 7 is a view similar to Figure 2, taken on line 7—7 of Figure 6, and looking in the direction of the arrows.

Figure 8 is a diagrammatic representation similar to Figure 5, showing a modified alarm circuit for use in connection with the construction shown in Figure 6.

Referring to the above drawings, particularly to Figures 1, 2, 3, 4 and 5, a plurality of conduits are shown at 10, these conduits being spaced at equal radii and communicating with a detecting chamber 11 within housing 12. Figure 2 illustrates the manner in which the conduits are connected to the housing 12. An outlet pipe 13 is also connected to the housing and to a suction fan 14. Fluid is thus drawn through the conduits 10 and chamber 11 and into the outlet pipe 13 by the fan 14.

A shaft 15 is journaled within the housing 12 and is rotated by means of a motor 16 which is connected to the shaft 15 through a clutch having a fixed plate 17 and a slideable plate 18. The slideable plate 18 is suitably keyed to the shaft 15 and held normally in engagement with plate 17 by means of a spring 19 which is seated against a collar 20 pinned to the shaft 15. An arm 21 is pivoted at 22 and formed with a forked extremity 23 to engage a flange 24, formed on plate 18 to de-clutch the plates 17 and 18 and thus stop the ro-

tation of the shaft 15. An electro-magnet 25 actuates a plunger or armature 26 which is pivotally connected to the arm 21, thus affording an electrical means for actuating the clutch. After 5 the plate 18 has disengaged the plate 17 it moves into engagement with a stationary bracket 27 which has a friction plate 28 and thus continues rotation of the shaft 15, after declutching, is prevented.

10 Upon the shaft 15 and within the housing 12, a rotating disc 29 is mounted, the disc being formed with a duct 30 which communicates with a conduit 31 for applying fluid to a detecting chamber 32. The disc 29 is formed with an offset housing 33 to cooperate with the ends of the conduits successively and thus effectively connect the duct 30 therewith. As the disc rotates, therefore, the conduit 30 is brought into communication with the respective conduits and fluid from the latter 20 directed into the detecting chamber 32. The housing 12 is formed with a window 34 and disc 29 is provided with a skirt 35 upon which suitable indicia may be inscribed in order that the device may indicate under which conduit the conduit 25 30 is positioned at a given instant.

The conduit 13 is provided with a branch 36 which communicates with the detecting chamber 32 and thus creates a vacuum therein to draw fluid from the conduit 31 through the chamber and to 30 the fan 14. If desired, the fan may be provided with an exhaust conduit 37 which discharges the fluid into a chamber 38 in which a light source 39 is mounted, an outlet 40 being provided therefrom. In this fashion, the light source 39 is effectively 35 cooled by the fluid flow from the conduit 37.

Within the detecting chamber 32, a photo-electric cell 41 is mounted, this cell preferably being provided with a compartment 41' across which the rays of light from lamp 39 pass as indicated in 40 dot and dash lines in Figure 1. The light from lamp 39 may be suitably focused by means of a lens 42 mounted in an aperture of one wall of the housing which forms the chamber 32. In this fashion, smoke particles within the chamber 32 45 increase the light intensity in front of the photo-electric cell by reflection and cause the same to be actuated.

The photo-electric cell 41 is adapted to be connected across a resistance 43 and battery 44 by 50 means of a switch 45. The voltage across resistance 43 is applied to the grid of a three element thermionic tube 46, the plate circuit of which tube is shown at 47 and includes a relay 48. In the form shown, in Figure 5, relay 48 is provided with 55 three contacts 49, 50, and 51, respectively. Contact 51 is adapted to close a stick circuit 52 including a battery 53 whereby a momentary impulse sufficient to actuate the relay causes the same to be permanently energized. The relay is deenergized by means of a manual switch 54 in the stick circuit 52.

A contact 50 is connected to a circuit 55 in which a bell or other suitable alarm or indicating device 56 is connected while contact 49 is connected in a circuit 57 in which the electro-magnet 25 is connected.

From the foregoing, it will be seen that when 70 switch 45 is closed and the photo-electric cell is in a non-illuminated condition there is no passage of electrons through the cell and therefore an open gap in the circuit exists. The elements of the system are so related that the potential of the grid of the thermionic tube 46 is practically the same as that of the terminal of the photo-electric cell, the system then being in a non-indicat-

ing condition. When, however, smoke particles or other suspended matter in the fluid stream reaches the detecting chamber and the light cast upon the cell increases, the resistance of the cell is decreased and current flows through the 5 resistance 43. This causes a corresponding change in the potential of the grid of the thermionic tube 46 and a flow of amplifying current in the plate circuit takes place to operate relay 48.

As described above, actuation of the relay causes 10 the same to be connected in a closed circuit with battery 53 and thus the contacts are held closed, while the alarm 56 is sounded and the motor 16 declutched from shaft 15. By observing the position of the disc 29, as displayed through window 15 34, the location of the smoke may be determined and suitable action instituted.

In the construction shown in Figures 6, 7, and 8, the elements for effecting the detection of smoke particles or other suspended matter are identical 20 to those described in the construction shown in Figure 1. The mechanism, however, for determining the location of the condition is slightly different and includes a visual detector comprising windows 58 in each of the conduits 10. The 25 conduits are formed with light tube extensions 59 having apertures 60 within which light from a light source 61 is directed. Suitable reflecting means 60' may be provided in the ends of the tubes 59 to direct the light rays down the tubes and 30 conduits 10 past the windows 58. In this fashion, existence of smoke particles in any of the conduits 10 gives rise to an illumination back of the corresponding windows 58, thus identifying the exact location of the condition. The electrical circuit for operating the alarm mechanism of the construction shown in Figure 6 is illustrated by the diagram of Figure 8. In this circuit the elements are identical to those shown in Figure 5 35 except that the electro-magnet 25 and its corresponding circuit 57 is eliminated in as much as there is no declutching arrangement between the driving motor 16 and the rotating disc 29.

From the foregoing, it will be seen that a mechanism has been provided for detecting the existence of smoke or other similar conditions by 45 means of a single detector, the detector being of such construction that a persisting indication is given even if only a momentary condition exists in any of the protected areas. Means is thus provided for effecting a visual indication automatically, as well as effecting an indication upon even a momentary passage of foreign matter through a conduit.

The foregoing mechanism provides for a substantially continuous suction through all of the fluid stream conduits including the particular fluid stream conduit being supervised at any instant. In this fashion, the motion of the fluid through the conduits is substantially continuous and no delay is permitted in the movement of the fluid between the protected and the detecting device.

While the invention has been described with specific reference to the accompanying drawings, 65 it is not to be limited, save as defined in the appended claims.

I claim as my invention:

1. A device for detecting suspended matter in 70 fluids comprising a plurality of fluid sources terminating in openings arranged in a circular path, means responsive to the presence of opaque suspended matter in fluids, a rotatable member formed with a conduit adapted to communicate with said openings to connect the responsive 75

means with the sources successively, means to direct a fluid flow from the sources substantially continuously, means to rotate the member, and means actuated by the responsive means to resist rotation of the member upon passage of suspended matter through the responsive means.

5. A device for detecting suspended matter in fluids comprising a plurality of fluid sources terminating in openings arranged in a circular path, means responsive to the presence of opaque suspended matter in fluids, a rotatable member formed with a conduit adapted to communicate with said openings to connect the responsive means with the sources successively, means to direct a fluid flow from the sources substantially continuously, means to rotate the member, a clutch between the member and the rotating means, and means responsive to actuation of the responsive means to disengage the clutch upon 15 passage of suspended matter through the responsive means.

6. A device for detecting suspended matter in fluids comprising a plurality of fluid sources terminating in openings arranged in a circular path, means responsive to the presence of opaque suspended matter in fluids, a rotatable member formed with a conduit adapted to communicate with said openings to connect the responsive means with the sources successively, means to direct a fluid flow from the sources substantially continuously, means to rotate the member, a clutch between the member and the rotating means, and means responsive to actuation of the responsive means to disengage the clutch upon 20 passage of suspended matter through the responsive means.

7. A device for detecting suspended matter in fluids comprising a plurality of fluid sources terminating in openings arranged in a circular path,

means responsive to the presence of opaque suspended matter in fluids, a rotatable member formed with a conduit adapted to communicate with said openings to connect the responsive means with the sources successively, means to direct a fluid flow from the sources substantially continuously, means to rotate the member, a clutch between the member and the rotating means, and means responsive to actuation of the responsive means to actuate the clutch and apply a restraining force to the member to resist 25 rotation thereof upon passage of suspended matter through the responsive means.

8. A device for detecting suspended matter in fluids comprising a plurality of fluid sources terminating in openings arranged in a circular path, means responsive to the presence of opaque suspended matter in fluids, a rotatable member formed with a conduit adapted to communicate with said openings to connect the responsive means with the sources successively, means to direct a fluid flow from the sources substantially continuously, means to rotate the member, a clutch between the member and the rotating means, and means responsive to actuation of the responsive means to actuate the clutch, and indicating means rotatable with the member to indicate the connection established between the responsive means and the sources upon passage of suspended matter through the responsive means.

9. A device for detecting suspended matter in fluids comprising a plurality of fluid sources terminating in openings arranged in a circular path, means responsive to the presence of opaque suspended matter in fluids, a rotatable member formed with a conduit adapted to communicate with said openings to connect the responsive means with the sources successively, means to direct a fluid flow from the sources substantially continuously, means to rotate the member, a clutch between the member and the rotating means, and means responsive to actuation of the responsive means to actuate the clutch, and means actuated by the responsive means to maintain the clutch in the said actuated condition upon

passage of suspended matter through the responsive means.

10. A device for detecting suspended matter in fluids comprising a plurality of fluid sources, means responsive to the presence of opaque suspended matter in fluids, means to connect the responsive means successively to the sources to shunt the fluid flow from the sources successively through the responsive means, the responsive means being relatively near the last named connecting means, means to maintain a fluid flow from the sources substantially continuously, and means to permit visual inspection of the fluid from the respective sources.

11. A device for detecting suspended matter in fluids comprising a plurality of fluid sources, means responsive to the presence of suspended opaque matter in fluids, a rotatable member to effect connection of the responsive means with the sources successively, means to direct a fluid flow from the sources substantially continuously, means to rotate the member, a clutch-like member between the rotatable member and the rotating means, and means responsive to the actuation of the responsive means to disengage the clutch-like member upon passage of suspended matter through the responsive means.

12. A device for detecting suspended matter in fluids comprising a plurality of fluid sources, means responsive to the presence of suspended opaque matter in fluids, a rotatable member to effect connection of the responsive means with the sources successively, means to direct a fluid flow from the sources substantially continuously, means to rotate the member, a clutch-like member between the rotatable member and the rotating means, means responsive to actuation of the responsive means to actuate the clutch-like member, upon passage of suspended matter through the responsive means and indicating means rotatable with the rotatable member to indicate the connection established between the responsive means and the sources.

13. A device for detecting suspended matter in fluids comprising a plurality of fluid sources, means responsive to the presence of suspended opaque matter in fluids, a rotatable member to effect connection of the responsive means with the sources successively, means to direct a fluid flow from the sources substantially continuously, means to rotate the member, a clutch-like member between the rotatable member and the rotating means, means responsive to actuation of the responsive means to actuate the clutch-like member, and means actuated by the responsive means to maintain the clutch-like member in the said actuated condition upon passage of suspended matter through the responsive means.

14. A device for detecting suspended matter in fluids comprising a plurality of fluid sources, means responsive to the presence of suspended opaque matter in fluids, a rotatable member to effect connection of the responsive means with the sources successively, means to direct a fluid flow from the sources substantially continuously, means to rotate the member, and means actuated by the responsive means to resist rotation of the member upon passage of suspended matter through the responsive means.

CERTIFICATE OF CORRECTION.

Patent No. 2,033,466.

March 10, 1936.

HARRY CAMPBELL GRANT, JR.

It is hereby certified that error appears in the above numbered patent requiring correction as follows: In the grant, name of the patentee, for "Henry Campbell Grant, Jr." read Harry Campbell Grant, Jr.; page 2, second column, line 62, after the word "protected" insert areas; and that the said Letters Patent should be read with these corrections therein that the same may conform to the record of the case in the Patent Office.

Signed and sealed this 14th day of April, A. D. 1936.

Leslie Frazer
Acting Commissioner of Patents.
